US00D632020S

(12) **United States Design Patent**
Onrot et al.

(10) **Patent No.:** **US D632,020 S**
(45) **Date of Patent:** **** Feb. 1, 2011**

(54) **COMPLIANT IMPACT PROTECTION PAD**

(75) Inventors: **Martin Paul Onrot**, Montréal (CA); **Iris Grant Onrot**, Tampa, FL (US)

(73) Assignee: **ComfiHips, LLC**, Tampa, FL (US)

(**) Term: **14 Years**

(21) Appl. No.: **29/363,842**

(22) Filed: **Jun. 15, 2010**

Related U.S. Application Data

(62) Division of application No. 12/401,265, filed on Mar. 10, 2009.

(51) **LOC (9) Cl.** **29-02**

(52) **U.S. Cl.** **D29/120.1**

(58) **Field of Classification Search** D29/100, D29/101.1, 101.2, 101.3, 101.4, 101.5, 120.1, D29/120.2, 121.1, 121.2, 122; D2/858, 712, D2/901; D24/189, 190; 2/16, 20-24, 62, 2/267, 455, 459, 461-468, 910, 911; 602/3, 602/5, 6, 15, 23, 26

(57) **CLAIM**

The ornamental design for compliant impact protection pad, as shown and described.

DESCRIPTION

FIG. 1 is a perspective view of a compliant impact protection pad of the present invention;

FIG. 2 is a top plan view of a compliant impact protection pad shown in FIG. 1;

FIG. 3 is an end view of a compliant impact protection pad shown in FIG. 1;

FIG. 4 is a left side view of a compliant impact protection pad shown in FIG. 1, the right side view being a mirror image thereof; and,

FIG. 5 is a bottom view of a compliant impact protection pad shown in FIG. 1.
